UNITED STATES PATENT OFFICE.

CHARLES HAMILTON PAJEAU, OF EVANSTON, ILLINOIS.

ALPHABETICAL CONSTRUCTION TOY.

1,241,009.

Specification of Letters Patent. Patented Sept. 25, 1917.

Application filed February 1, 1917. Serial No. 145,848.

To all whom it may concern:

Be it known that I, CHARLES HAMILTON PAJEAU, citizen of the United States, residing at Evanston, Illinois, have invented 5 certain new and useful Improvements in Alphabetical Construction Toys; and I do hereby declare the following to be a full, clear, and exact description of the invention, such as will enable others skilled in the art 10 to which it appertains to make and use the same.

My invention relates to educational toys, its general objects being to provide an inexpensive but fascinating combination of a 15 structural and an alphabetical toy, and to provide unusually effective means for displaying such a toy. In marketing goods of this general class, the sales depend to a large extent upon the manner in which the 20 goods are presented; that is to say, upon the effectiveness with which the toy-buying parent can be made to see the real nature and purposes of what is offered to him. Owing to the limited display space on the surface 25 of the packages containing such toys, it is usually impossible to present sufficiently large pictures on the box labels to show the use of the box contents to the casual observer. To be effective, such pictures would 30 have to be of a size for which the average storekeeper has no room on his toy counters or in his store windows. On the other hand, the presentation of the toy or game by a demonstrator involves an expense out of 35 portion to the retailer's usual profit on the sales and demands expert service which is not commonly available, hence the selling of such articles has been seriously handicapped.

To overcome this handicap, particularly 40 in connection with educational toys intended for word-building, I pack such a set of elements in a container shaped and marked to form a mammoth reproduction of certain of the distinctive elements comprising the set, 45 and also pack in this container correspondingly proportioned auxiliary means adapted to coöperate with the container for constituting a complete enlarged representation of any of the numerous members which may be 50 constructed from the set. For example, in providing alphabet blocks for use in word-building, I use blocks 1 each having on at least one face a letter, the blocks being of the same shape and desirably also of the 55 same size. To display these blocks please-

ingly and to add to the child's fascination in playing with the same, I preferably provide a detachable pedestal, as for example by providing dowels 2 interchangeably fitting bores in the bottom of the blocks and in bases 60 3, as illustrated in Figure 2. All of these parts are preferably packed while disassembled, so as to afford the user the pleasure of constructing or assembling these elements in the form shown in Fig. 4 of the drawings. 65 These parts are all packed in a box which also provides storage room for mammoth reproductions of both the dowel or pillar 2 and the base 3. The giant pillar 2^A is equipped at its upper end for socketing in a bore in 70 the bottom of the box, as shown in Fig. 1, and at its lower end for socketing the same in the giant base 3^A, while the box 4 is shaped like any one of the blocks 1 and is equipped on at least one face with a letter 75 proportioned to the corresponding letter on one of the said blocks. Consequently, when these mammoth reproductions of the block, pillar and base portions of each word-building member of my set are assembled as 80 shown in Fig. 3, they constitute a giant facsimile of the word-building members. By thus using the container itself as one element of the display form of my toy, I am able to display the latter effectively on 85 counters and in show windows without resorting to posters, cutouts or other auxiliaries, the display effect being readily enhanced by also placing part of the assembled contents of the box alongside the latter. 90 Consequently, I am able to secure greatly increased sales without resorting to auxiliary advertising or employing demonstrators.

However, while I have shown separable 95 dowel and base portions as the means for holding each letter-block in effective position, and likewise for holding the letter-block-simulating box in display position, I do not wish to be limited to these or other 100 details of the construction and arrangement herein disclosed, it being obvious that the same might be modified in many ways without departing from the spirit of my invention.

I claim as my invention:

1. A set of alphabetical construction blocks each comprising a block equipped on one face with a letter of the alphabet, and an equal number of base elements and of 110

dowels, the blocks and base elements all having bores for interchangeably receiving opposite ends of the dowels.

2. The combination with a box, of a pedestal for supporting the box in an elevated position, the pedestal being detachable and normally housed by the box, and a plurality of legend-bearing members also normally housed by the box and each being a miniature reproduction of said box and pedestal.

3. The combination with a box having a perforation in its bottom, of a pedestal having an upper end adapted to socket in said perforation, a plurality of miniature reproductions of the pedestal, and a plurality of miniature blocks of substantially the same

shape as said box and each arranged for mounting the same on one of the miniature pedestals, the said box normally serving as a container for all of the other elements 20 above recited.

4. The combination with a box, of elements all normally housed by the same; said elements comprising a support for holding the box in display position, blocks similar 25 in shape to the box and respectively marked with different legends, and miniature supports simulating the aforesaid support and arranged respectively for similarly holding said blocks.

Signed at Evanston, Ill., January 30, 1917.
CHARLES HAMILTON PAJEAU.
